UNITED STATES PATENT OFFICE.

HARRY M. BRANDT AND ELMER ESSLEY, OF CANTON, KANSAS.

DESIGN FOR A BUTTER-STAMPING BLOCK.

SPECIFICATION forming part of Design No. 29,302, dated September 6, 1898.

Application filed May 24, 1897. Serial No. 637,967. Term of patent 14 years.

To all whom it may concern:

Be it known that we, HARRY M. BRANDT and ELMER ESSLEY, of Canton, McPherson county, Kansas, have invented and produced 5 a new and original Design for a Stamping-Block, of which the following is a full, clear, and exact description, reference being had to the accompanying drawing, forming a part thereof.

10 The drawing represents a perspective view of a stamping-block; and the leading feature of our design consists of a rectangular stamping-block having a border parallel with its margin inclosing a pair of raised duplicate 15 panels, said border consisting of an oblong rectangular channel having a series of raised figures or squares therein.

In the drawing, 1 designates the rectangular face of the block; 2, the pair of raised duplicate panels; 3, the oblong rectangular channel, and 4 the series of raised figures or squares within said channel.

What we claim is—

The design for a stamping-block, as herein shown and described. 25

In testimony whereof we affix our signatures in the presence of two witnesses.

HARRY M. BRANDT.
ELMER ESSLEY.
